Inventor:

Edmond Picard

By *June Daniels*
Attorney

UNITED STATES PATENT OFFICE.

EDMOND PICARD, OF PARIS, FRANCE.

VARIABLE CONDENSER.

Application filed June 19, 1925, Serial No. 38,253, and in France October 4, 1924.

My invention relates to variable condensers comprising stationary and movable plates whereof the relative rotation will vary the operative surface of the condenser.

5 According to the invention, in addition to its rapid movement of rotation which is effected by means of a control knob or dial secured to the shaft, the movable or rotor plates may be given very fine displacements, 10 these being produced by the rotation of an arm which is mounted at one end with considerable friction upon the rotor and is connected at the other end with a bell crank lever whose free end can be more or less 15 shifted by a hand controlled screw. The pitch of the screw and the length of the lever arm may be suitably chosen in order to obtain a very slight movement of the rotor even for a considerable rotation of the screw 20 knob.

The appended drawings which are given by way of example show an embodiment of my said invention as applicable to an air condenser for radio telegraphy or telephony.

25 Fig. 1 is a perspective view of the condenser.

Fig. 2 is an axial section thereof.

In the said figures, 3 is the stationary member of the condenser which is composed 30 of a plurality of metallic plates in parallel disposition which are maintained between two cheeks or end plates 4 and 5 consisting of insulation and spaced apart by the cross-pieces 6.

35 Forwardly of the said stationary member is disposed the shaft 7 carrying the movable member or rotor 8 which likewise consists of corresponding parallel metallic plates which by the rotation of the shaft 7 may be moved, 40 without contact, through the spaces between the plates of the stationary member. To effect this the said shaft is mounted in bearings provided in the end plates 4 and 5 and has disposed upon its upper part the milled 45 knob 9.

In accordance with my invention, there is mounted with considerable friction on the shaft 7 an arm 10 which is held between two spring washers 11 and 12 which are maintained upon the shaft 7 for instance by a nut. The outer or free end of the arm 10 is pivoted at 13 to the short arm of a bell-crank lever 14 which is pivoted upon an axle 15 carried by a strap or bracket that is

mounted on the upper plate 5. The long 55 arm of said lever terminates in a fork 16 which is engaged between the two shoulders 17 and 18 of a screw 19 engaging in a tapped hole in the plate 5 and having at the top a special button 20. 60

A spring 21 which is attached at one end to one of the cross-pieces 6 and at the other to the arm 10, tends to move the rotor in a given direction and obviates all effect of play in the joints; said spring may further 65 assure the electrical connection between the rotor and the cross-piece, which latter, as shown, will in such event comprise a terminal 26.

The variable condenser according to my 70 invention is operated in a very simple manner. The dial knob 9 is turned in order to rotate the shaft 7, but without effect upon the arm 10, and this affords an approximate adjustment of the capacity of the condenser. 75 An accurate or fine adjustment is obtained by turning the button 20 of the screw 19 whose motion, which can be as slight as desired, will rock the lever 14 about its pivot and provide for a very slight rotation of the 80 axle 7 and the rotor 8.

It is further to be noted that by a suitable choice of the length of the arm 10 and of the ratio between the arms of the lever 14, I may obtain a very slight rotation of the 85 shaft 7 per revolution of the screw 19.

The friction of the arm 10 between the washers 11 and 12 must be greater than the friction of the shaft 7 in its bearings. Fig. 2 shows an arrangement which offers excellent 90 results for this purpose. At the ends of the shaft 7 are the two journals 21 and 22, respectively engaged in the screwthreaded bearings 23 and 24 which are screwed into the end plates 4, 5. The movement of the 95 said journals is limited by a tapered shoulder 25 engaging a corresponding tapered recess in the bearing 23 or 24. The contact between the said shoulder and recess will also provide for an exact vertical adjustment of 100 the rotor.

Obviously, my said invention is not limited to the type of air condenser hereinbefore set forth, but is applicable to all condensers having a movable element co-operating with a stationary element. 105

The invention is further applicable not only to condensers but also to a great num-

ber of other apparatus in which it is desired to obtain an accurate adjustment, and chiefly for variometers.

I claim as my invention:

6. 1. An instrument comprising rotor and stator members, a shaft whereon the rotor is mounted, a handle for rotating said shaft to effect coarse adjustment of the rotor, and a device for effecting fine adjustment of the 10 rotor; said device embodying an arm frictionally mounted on the rotor shaft, a bell-crank lever having one end thereof pivoted to said arm, and an operating screw connected with the other end of the bell-crank 15 to rock the same and thereby turn said arm and shaft.
2. An instrument comprising rotor and stator members, a shaft whereon the rotor is mounted, a handle for rotating said shaft 20 to effect coarse adjustment of the rotor, and a device for effecting fine adjustment of the rotor; said device embodying an arm frictionally mounted on the rotor shaft, a rocking element provided at one end with a fork 25 and connected at the other end to said arm, and an operating screw engaged in said fork to rock said element when turned and thereby turn said arm and shaft.
3. An instrument comprising rotor and 30 stator members, a shaft whereon the rotor is mounted, a handle for rotating said shaft to effect coarse adjustment of the rotor, and a device for effecting fine adjustment of the rotor; said device embodying an arm frictionally mounted on the rotor shaft, a rock- 35 ing element provided at one end with a fork and connected at the other end to said arm, and an operating screw having a pair of spaced shoulders between which the members of said fork are slidably engaged to rock said element when turned and thereby turn said arm and shaft.
4. An instrument comprising rotor and stator members, a shaft whereon the rotor is mounted, a handle for rotating said shaft to effect coarse adjustment of the rotor, and a device for effecting fine adjustment of the 40 rotor; said device embodying an arm frictionally mounted on the rotor shaft, a bell-crank lever having one end thereof pivoted to said arm and provided at its other end with a fork, and an operating screw having a pair of spaced shoulders between which the members of said fork are slidably engaged to rock said bell-crank when turned and thereby turn said arm and shaft.
5. An instrument comprising rotor and stator members, a shaft whereon the rotor is mounted, a handle for rotating said shaft to effect coarse adjustment of the rotor, a 45 device for effecting fine adjustment of the rotor; said device embodying an arm frictionally mounted on the rotor shaft, a bell-crank lever having one end thereof pivoted to said arm, and an operating screw connected with the other end of the bell-crank to rock the same and thereby turn said arm and shaft; and a return spring connected at opposite ends to said arm and to the 50 stator.

In testimony whereof I affix my signature.
EDMOND PICARD.
